INSTRUMENT HOUSING

Robert B. Bagshaw, Huntingdon, Pa., assignor to Wald Industries, Inc., Huntingdon, Pa., a corporation of Pennsylvania

Filed Dec. 29, 1961, Ser. No. 68,129

Term of patent 14 years

(Cl. D26—1)

FIG. 1.

FIG. 2.

FIG. 1 is a view in perspective looking down on the right side and the front of the instrument housing; and

FIG. 2 is a view in perspective looking down on the rear and left side of said instrument housing.

The bottom of said housing, not shown in the drawings, is a plain flat surface.

The dominant features of my design are shown in solid lines in the drawing.

I claim:

The ornamental design for an instrument housing, as shown and described.
